FUEL MIXER

Percy D. Hutton, Buffalo, N. Y.

Application June 2, 1945, Serial No. 597,360

2 Claims. (Cl. 261—13)

1

This invention relates to fuel mixers, and more particularly to liquid fuel and air mixing devices for use in conjunction with internal combustion engines or liquid fuel burning heating devices and the like.

One of the objects of the invention is to provide an improved fuel and air mixing device such as may be employed either as the sole carburetion device in conjunction with an internal combustion engine or the like, or as an accessory to a conventional type carburetor. Another object of the invention is to provide a fuel-air mixing device which is adapted to provide more efficient mixing of air and fuel when employed in conjunction with either an internal combustion engine or a fuel oil burner or the like.

Another object of the invention is to provide an improved fuel-air mixer which is adapted to procure more efficient gasification of a liquid fuel. Another object of the invention is to provide an improved fuel-air mixing device which is adapted to procure more efficient gasification of the liquid fuel and more efficient admixing of air and the gasified fuel.

Another object of the invention is to provide the features and advantages aforesaid while delivering to the mixed fuel consumer a fuel-air mixture of reduced temperature. Another object of the invention is to provide a device which is adapted to provide the features and advantages aforesaid while comprising a mechanical structure which is simple and inexpensive to manufacture and service. Other objects and advantages of the invention will appear from the specification hereinafter.

In the drawing:

Fig. 1 is a fragmentary side elevation, with portions broken away to show the interior of a fuel-air mixing device of the invention;

Fig. 2 is a fragmentary section as along line II—II of Fig. 1; and

Fig. 3 is a fragmentary section along line III—III of Fig. 1.

The drawing illustrates, for example, one physical form in which the device of the invention may be constructed; and as shown therein the device includes a mixed fuel delivery conduit 10 adapted to be connected as at the flanged end 12 to the intake manifold or other fuel conveying conduit of the engine or burner to be fed by the fuel mixer. A conventional type throttle valve 14 is shown in the conduit 10 for either manual or automatic control to regulate the flow of fuel-air mixture to the engine to be serviced. The fuel discharge conduit 10 leads to a ported

portion of a generally cylindrical shaped casing 18 which comprises the mixing chamber of the device. A heating element is disposed within the mixing chamber 18; and as shown in the drawing, the heating element may comprise a conduit 20 arranged to convey a heating medium such as the exhaust gases from the engine or burner to be serviced by the mixer. The conduit 20 is illustrated in the drawing to include a swelled portion 22 interiorly of the mixing chamber; said swelled portion 22 being streamline shaped in sectional view as shown in Fig. 2 and formed with exteriorly extending fin devices 24 to increase the heat exchange surface area of the hot jacket 15 portion 22.

The mixing chamber 18 includes a second ported portion 26 which leads to an air intake 28; and as shown in the drawing the air inlet and mixed fuel discharge conduits 10—26 are disposed in vertically aligned relation so as to enter into open communication with the interior of the mixing chamber 18 at diametrically opposed positions thereon.

A fuel supply chamber is provided as indicated 25 at 30 to supply liquid fuel to the mixer device through means of a conduit 32 which terminates in a jet 33. It will be understood of course that the fuel supply chamber 30 may be of any suitable type so as to be adapted to furnish fuel to the mixer as required; and may for example comprise a pair of separate float-controlled reservoirs 34—35 in which the fuel liquid levels are suitably maintained by float devices or the like and from which liquid fuel may be alternately drawn into 35 the feeding nozzle 33 as controlled by a duplex toggle valve 36. Thus, for example, the chamber 34 may be connected to a supply of "starting" fuel such as gasoline and the chamber 35 connected to a supply of "running" fuel such as "fuel oil"; and either low grade or high grade fuel may be fed to the mixer as the operator desires by simple adjustment of the valve 36.

The fuel feed nozzle 33 is disposed to discharge the fuel into a pre-mixing cuff 40 which substantially encloses the hot jacket portion 22. The cuff 40 includes a feed throat 42 which receives the fuel nozzle 33 and also provides a reduced air inlet opening 44. The cuff 40 enlarges laterally in all directions from the position of the throat 42 so as to encompass the hot jacket 22 in spaced relation therefrom whereby to provide a fuel and air mixing space surrounding the hot jacket 22 and interiorly of the cuff 40. In end view the cuff 40 is streamline shaped so as to complement the shape of the hot jacket 22 while

being spaced therefrom and also spaced interiorly of the mixing chamber wall 18. The bottom portion of the pre-mixing cuff 40 is perforated as indicated at 45 so as to permit dispersed escape of mixed fuel and air therefrom, and may also be saw-slotted as indicated at 46.

Thus, it will be understood that whenever the mixer device of the invention is installed in conjunction with an internal combustion engine or a fuel burner or the like and when the throttle valve 14 is open and the engine is operating to impose a suction force upon the mixer discharge conduit 10, the interior of the mixer device will be subjected to a partial vacuum whereby air will be drawn into the intake 28. If the fuel feed control valve 36 is also open a supply of liquid fuel will simultaneously be sucked from the jet 33 as a result of the rush of a portion of the intake air which enters the cuff through the air gap 44 to pass by the jet 33 thereby inducing flow of liquid fuel therefrom.

As the fuel sprays out of the jet 33 it mixes with the relatively small volume of air entering the cuff throat 42 and impinges with the accompanying air against the hot jacket 22 to become heated and gasified and intimately mixed and absorbed in the air passing through the cuff 40. Thus, optimum gasification of the liquid fuel is accomplished under relatively high temperature conditions while employing only a small portion of the total amount of air which is ultimately required for complete combustion of the fuel. This pre-mixed fuel and air component discharges through the openings 45-46 at the bottom of the cuff 40 and into the main mixing chamber 18 where it becomes entrained in uniformly mixed fashion within the body of the main portion of air entering the intake 28.

In this manner a completely gasified fuel component is added to the major portion of the air required to be furnished for complete combustion of the fuel, and inasmuch as the fuel component has been initially pre-mixed with hot air for complete gasification, it is not necessary that the major portion of the air supply be heated in order to obtain an ultimate fuel-air mixture of optimum combustion characteristics. Consequently, it is arranged that the major portion of the air supply be permitted to pass through the mixer without substantial heating thereof prior to being mixed with the pre-mixed fuel-air component in the lower portion of the mixing chamber, and a relatively cool but completely gasified fuel-air mixture is thereby delivered to the engine or burner being served.

As illustrated at 50, a water supply chamber may be conveniently mounted adjacent the inlet conduit 26 to provide for introduction of water into the pre-mixing chamber whenever the operation is to be benefited by addition of water vapor to the fuel air mixture. In such case the chamber 50 will be suitably controlled, as by a float level control device or the like, so that the water supply therein will be maintained at substantially constant level, and a discharge conduit as indicated at 52 will be arranged to suck water out of the reservoir 50 for delivery into the conduit 26 at a position above the throat 42 of the pre-mixing cuff. Thus, it will be understood that flow of water into the intake airstream will be induced in response to the rush of intake air passing through the conduit 26 and the cuff throat 42. A control valve as at 54 may be supplied to

enable the operator to control the water feed arrangement.

Thus, it will be understood that the invention provides a particularly compact and structurally simple fuel mixing device which is adapted to provide improved degree of fuel gasification while delivering a fuel-air mixture of reduced temperature. It will also be appreciated that the apparatus of the invention may be very inexpensively constructed and assembled from metal parts such as are easily and inexpensively manufactured by standard shop methods and tools. It will also be understood that although only one specific form of fuel mixer of the invention has been illustrated and described herein, and that only a few of the possible applications of the mixer of the invention have been discussed herein; the invention is not so limited, and various changes may be made in the structural design and applications thereof without departing from the spirit of the invention and the scope of the appended claims.

I claim:

1. A liquid fuel and air mixer comprising a horizontally arranged cylindrical mixing chamber having an upwardly extending single air intake duct and a mixture outlet, a pre-mixing cuff in spaced nested relation with the wall of the mixing chamber, said cuff having an upwardly extending intake throat substantially concentric with and projected into the air intake duct of said mixing chamber for receiving a portion of the air supplied through said duct, said cuff being formed with outlet perforations formed along its lower side and in communication with the mixture outlet of the mixing chamber, a fuel nozzle for supplying liquid fuel to said throat, and a heating jacket extending through and in spaced nested relation to said cuff.

2. A liquid fuel and air mixer comprising a horizontally arranged cylindrical mixing chamber having an upwardly extending single air intake duct and a mixture outlet, a pre-mixing cuff in spaced nested relation with the wall of the mixing chamber, said cuff having an upwardly extending intake throat substantially concentric with and projected into the air intake duct of said mixing chamber for receiving a portion of the air supplied through said duct, said cuff being formed with outlet perforations formed along its lower side and in communication with the mixture outlet of the mixing chamber, a fuel nozzle for supplying liquid fuel to said throat, a heating jacket extending through and in spaced nested relation to said cuff, said jacket having a swelled portion of streamlined cross section disposed within said cuff, and an exteriorly extending fin device surrounding said swelled portion.
